UNITED STATES PATENT OFFICE.

JOHN W. LANGFITT, OF ADEL, IOWA.

ROAD-GRADER.

No. 839,069.

Specification of Letters Patent.

Patented Dec. 18, 1906.

Application filed April 18, 1906. Serial No. 312,362.

To all whom it may concern:

Be it known that I, JOHN W. LANGFITT, a citizen of the United States, residing at Adel, in the county of Dallas and State of Iowa, have invented a certain new and useful Road-Grader, of which the following is a specification.

The object of my invention is to provide a road-grader of simple, durable, and inexpensive construction in which two blades are provided to stand on opposite sides of the longitudinal center of the machine and at acute angles relative to the line of advance to scrape earth toward the center of the machine and to provide means for independently adjusting the blades toward and from the center of the machine, and also to independently adjust each blade up and down from a position engaging the road-surface to a position at rest above the machine-frame.

A further object is to provide means whereby the frame that supports the blades may freely tilt relative to the front axle to a limited extent, so that the blades and supporting-wheels will automatically accommodate themselves to slight inequalities in the road-surface without throwing an undue strain upon either blade.

A further object is to provide a steering-wheel at the rear of the machine capable of being operated to cause the rear end of the machine to advance out of line with the front end, so that either blade may be directed to advance more nearly in a line parallel with the longitudinal center of the machine to thereby cut more deeply into the road-surface.

A further object is to provide improved means for independently tilting the blades to change the angles at which they engage the road-surface relative to a vertical line.

My invention consists in certain details in the construction, arrangement, and combination of the various parts of the machine whereby the objects contemplated are attained, as hereinafter more fully set forth, pointed out in my claims, and illustrated in the accompanying drawings, in which—

Figure 1 shows a top or plan view of a complete machine embodying my invention. Fig. 2 shows a side elevation of same. Fig. 3 shows a front end elevation of same with one of the scraper-blades thrown to its elevated position on top of a frame. Fig. 4 shows a detail perspective view illustrating the rear end of the machine and the means

for steering it and raising and lowering it, and Fig. 5 shows a detail perspective view of a modified form of device for supporting the scraper-blades whereby they may be tilted relative to a vertical line.

Referring to the accompanying drawings, I have used the reference-numeral 10 to indicate a forward axle, having on its ends the supporting-wheels 11.

The machine-frame comprises two parallel center beams 12, extending the full length of the machine and projecting over the axle 10 and in front of it, the tongue 13 being pivoted between the forward ends thereof. Immediately in the rear of the axle 10 is a cross-beam 13, connected at its center with the axle 10 by means of the bolt 14, which permits the beam 13 to tilt freely relative to the axle. The beams 12 stand a slight distance above the axle 10 to permit a slight tilting movement of the beam 13. Two beams 15 are also provided which extend from a point at the forward end of the machine above the axle 10 rearwardly and inwardly toward the center of the machine. These beams 15 are attached to the cross-beams 13, and shoulders 16 are formed in the forward ends to receive the ends of the axle 10, and in this way to permit a limited tilting movement of the cross-piece 13 relative to the axle. At the rear end of the machine-frame is a cross-piece 17, to which the beams 12 and the beams 15 are fixed. Erected on this cross-piece 17 is a stationary frame 18, having at its top a forwardly-projecting segmental rack 20.

The rear end of the machine is supported upon an axle 21, having two caster-wheels 22 fixed to its ends. At the center portion of the axle 21 is an upright 23, inclined first forwardly and then upwardly and mounted in the cross-piece 17 and frame 18, its upper end being angular at 24. This angular upper end extends through a lever 25, which is held against vertical movement by the lugs 26, which permit it to rotate in a horizontal plane across the top of the rack 20. Mounted on the lever 25 is a spring-actuated pawl 27, controlled by a handle 28 and normally in engagement with rack 20. By this arrangement the rear end of the machine may be steered by the lever 25, and this lever may be set to any desired position and held therein by the pawl 27. Furthermore, the upright 23 may freely slide up and down without affecting the steering of the machine.

I have provided for raising and lowering the rear end of the machine, as follows: The numeral 29 indicates a stationary support in front of the upright 23, and having a segmental rack 30. Fulcrumed to this support 29 is a lever 31, provided with a spring-actuated pawl 32 to engage the rack 30. On the rear end of the lever is a link 33, pivoted to the upright 23. By this arrangement the rear end of the machine may be raised or lowered relative to the caster-wheels 22 by means of the lever 31, and the pawl 32 serves to lock it in any position in which it may be placed.

15 As will be seen in the drawings, there are two scraper-blades with independent means for operating them. These devices on the opposite side of the machine-frame are exact counterparts, and hence but one will be herein described.

The reference-numeral 34 indicates a rock-shaft having an angular body portion and rounded ends. The rear end is supported in a bearing-box 35, pivoted to the rear cross-piece 17, and the forward end is supported in a bearing-box 36, pivoted to a sliding supporting-bar 37. This sliding supporting-bar 37 extends across the machine-frame in the rear of the wheels 11 and between the transverse guides 38 and the longitudinal cleats 39 on the bar 12 and 15. At about the central portion of the rock-shaft 34 is another sliding supporting-bar 40, extended inwardly across the machine-frame and under the cleats 41. Mounted between the bars 37 and 40 is a beam 42, to which the blade raising and lowering means, hereinafter described, are attached. I have provided means for adjusting the parts 37 and for supporting them in their adjusted positions, as follows: Fixed to the beams 12 above the supporting-bar 37 is a segmental rack 43, and fulcrumed to the rack is a lever 44, carrying a spring-actuated pawl 45 to engage the rack 43. The lower end of the lever is slotted at 46 to admit a pin 47, carried by the bar 37. In this way a movement of the lever 44 will operate to slide the bar 37 toward or from the center of the machine, and 50 the pawl 45 will secure the lever in any position in which it is set.

I have provided means for independently raising and lowering the scraper-blade attached to the rock-shaft 34, as follows: Fixed to rock-shaft 34 are a number of curved arms 48, and on their outer ends is the scraper-blade 49. At the forward end of the scraper-blade I have provided a reinforcing cutting-blade 50, which may be detached when worn 60 and a new one substituted. I have provided a means for bodily raising and lowering each blade comprising a bevel gear-wheel 51, fixed to the rock-shaft 34. On the bar 42 is a bearing 51^a, in which the shaft 52 is rotatably mounted. Fixedly mounted on

the rock-shaft 34 is a bearing 53, which has a collar 54 to receive the shaft 52. A bevel gear-wheel 54 on the shaft 52 is in mesh with gear-wheel 51. On the upper end of the shaft 52 is a hand-wheel 56, by which the shaft 52 may be turned. In this way the rock-shaft 34 may be moved to raise and lower the scraper-blade 49 relative to the road-surface or to throw the blade upwardly over the top of the machine, as shown in Fig. 4, and when in this position the blades will not project beyond the sides of the machine-frame, and hence the machine may be driven through a gateway of ordinary width. I have provided for holding the shaft 52 in various positions, as follows: Connected with the bearing 51^a is an arm 57, to which a flexible band-brake 58 is attached. This band-brake passes around a small band-wheel 59 on the shaft 52, and attached to its other end is a link 60, to which the foot-lever 61 is pivoted. The operator may, by pressing his foot upon said lever, actuate the band-brake to hold the shaft 52 against rotation.

In some instances it is desirable to provide means for tilting the scraper-blade relative to the vertical line and I have shown a device for this purpose in Fig. 5. The scraper-blade is supported from the rock-shaft 34 by means of two arms 62, pivoted to the brackets 63 on the outer face of the blade. Attached to one of the arms 62 is a segmental rack 64, to which a lever 65 is fulcrumed. This lever is provided with a spring-actuated pawl 66, and its lower end is slidably connected to the slotted bracket 67, fixed to the upper edge portion of the blade 49. By this arrangement the operator may grasp the lever 65, and by manipulating it he may tilt the blade 49.

In practical use and assuming the parts to be adjusted to the positions shown in Figs. 1 and 2, then the machine is advanced by draft-animals over the road to be worked. The scraper-blades may be made to operate over a wide or narrow path by manipulating the levers 44. The operator may bodily raise and lower the blade by the hand-wheels 56, and the blades are held in their adjusted positions by the band-brakes 58. The rear end of the machine may be raised or lowered to suit the requirements by means of the levers 31. In steering the device under ordinary circumstances the caster-wheel is set to position in line with the long center of the machine. However, if it is desired to crowd the machine toward one side of the road, so that it will cut more deeply on one side than the other, the operator may set the steering-wheel so that it will direct the machine in the desired manner. During the ordinary operation of the machine when both blades are set to the position required for active work the front axle may have a slight tilting move-

ment relative to the machine-frame so as to adapt itself to inequalities of the road-surface.

Having thus described my invention, what I claim, and desire to secure by Letters Patent of the United States therefor, is—

1. In a road-scraper, the combination of a front axle, supporting-wheels thereon, a scraper-bearing frame having pivotal connection with the front axle, and means for limiting the pivotal movement of the frame relative to the axle.

2. In a road-scraper, the combination of a front axle, supporting-wheels mounted thereon, a frame converging toward the rear, and said frame pivotally mounted at its front end on the axle to permit a limited tilting movement of the ends of the axle relative to the frame, a rolling support for the rear end of the frame and two scraper-blades fixed to sides of the frame to engage the road-surface.

3. In a road-grader, a front axle, supporting-wheels thereon, a frame comprising a forward cross-piece, a bolt extended through the center of the axle and through the center of said cross-piece, arranged in a horizontal plane, to pivotally connect the cross-piece and axle, converging side beams connected with the cross-piece, having their front ends designed to engage the top of the axle and to limit the tilting movement of the cross-piece relative to the axle, two scraper-blades fixed to opposite sides of the machine and a caster-wheel for supporting the rear end of the frame.

4. In a road-scraper, the combination of a frame, supporting-wheels therefor, two rock-shafts supported by the frame and arranged on lines converging at the rear of the machine, arms connected with each rock-shaft, a scraper-blade carried by the said arms and means for swinging the scraper-blades from a position engaging the road-surface to a position resting on top of the frame.

5. In a road-scraper, the combination of a frame, supporting-wheels therefor, two rock-shafts supported by the frame and arranged on lines converging at the rear of the machine, arms connected with each rock-shaft, a scraper-blade carried by the said arms, means for swinging the scraper-blades from a position engaging the road-surface to a position resting on top of the frame, and means for adjusting the forward ends of said rock-shafts toward and from the longitudinal center of the machine.

6. In a road-scraper, the combination of a frame, supporting-wheels therefor, two rock-shafts supported by the frame and arranged on lines converging at the rear of the ma-

chine, arms connected with each rock-shaft, a scraper-blade carried by each set of arms means for swinging the scraper-blades from a position engaging the road-surface to a position resting on top of the frame, means for adjusting the forward ends of said rock-shafts toward and from the longitudinal center of the machine, and means for holding each rock-shaft in various positions.

7. In a road-scraper, the combination of a machine-frame, a rock-shaft extended from the forward end of the machine rearwardly and inwardly, bearing-boxes for the ends of the shaft mounted to swing in a horizontal plane, a cross-piece supporting the forward one of the said bearing-boxes and mounted slidingly on the frame, means for adjusting said cross-piece, a number of arms fixed to the rock-shaft, a scraper-blade carried by said arms, means carried by the frame for tilting the rock-shaft to move it from position engaging the road-surface to a position on top of the frame.

8. In a road-scraper, the combination of a front axle, supporting-wheels thereon, a frame having rearwardly-converging sides mounted on the front axle, the caster-wheel at the rear end of the frame, means for adjusting the rear end of the frame, up and down relative to the caster, means for steering the caster and two scraper-blades on opposite sides of the frame arranged on converging lines toward the rear end of the machine.

9. A road-scraper, comprising a frame, two supporting-wheels at the front of the frame, a caster-wheel at the rear of the frame, said frame capable of sliding vertically relative to the caster-wheel, means for raising and lowering the frame relative to the caster-wheel, means for securing the frame in different positions, a steering-lever slidingly connected to the top of the caster-wheel, a segmental rack adjacent to said lever, a spring-actuated pawl moved by the lever to engage the rack and two scraper-blades fixed to opposite sides of the machine-frame on lines converging toward the rear end of the machine.

10. In a road-grader, the combination of a scraper-blade, supporting-arms fixed to the outer face of the scraper-blade, a segmental rack fixed to one of said supporting-arms, a lever fulcrumed to the rack and slidingly connected with the upper portion of the scraper-blade, and a spring-actuated pawl moved by the lever for engaging the segmental rack.
